ANTICONVULSANT AGENTS

Henry Eugene Jean Marie Meunier, Grenoble, Isere, France, assignor to Chemetron Corporation, Chicago, Ill., a corporation of Delaware
No Drawing. Filed Dec. 17, 1963, Ser. No. 331,103
Claims priority, application France, Oct. 17, 1962, 912,469

23 Claims. (Cl. 167—65)

This application is a continuation-in-part of my application, Ser. No. 265,371, filed Mar. 15, 1963, and now abandoned.

This invention relates to a method of treating convulsions and seizures in warm-blooded animals. More particularly, the invention is concerned with treating epilepsy with dialkyl-substituted acetic acid and derivatives thereof.

The compounds of this invention which have been found to be effective in treating epilepsy in warm-blooded animals are characterized by the formula

wherein Alk_1 is a lower alkyl containing 2-7 carbon atoms inclusive and Alk_2 is a lower alkyl containing 3-7 carbon atoms inclusive; wherein Y is an OM group in which M is hydrogen or an alkali metal of Group IA of the Periodic Table of Elements including sodium and potassium; Y also is an OR radical where R is a lower alkyl either straight or branched chained containing 1-5 carbon atoms inclusive; Y further designates a NHZ group in which Z is hydrogen or carbamyl; and Y is still further a 5,5-diphenylhydantoinyl group. In the above formula, Alk_1 represents straight or branched chained lower alkyl such as ethyl; iso and n-propyl; as well as the normal, iso, secondary and tertiary isomers of the butyl, pentyl, hexyl and heptyl alkyls. Alk_2 likewise represents the same alkyls described for Alk_1 , except that the lowest alkyl is propyl.

There is a constant search for drugs effective for treating convulsions and for the control of the various types of epileptic conditions. While there are available many types of compounds useful as anticonvulsants, many of these compounds are highly toxic and cause serious side effects. Further, some of the well-known anticonvulsants agents are toxic at relatively low dosage levels. Others are useful for treating only one type of epilepsy.

It is therefore an object of this invention to provide novel anticonvulsant agents of low toxicity for treating convulsions and for the control of various types of epileptic seizures having a highly favorable therapeutic index; and having a chemical configuration entirely different from any of the well-known antiepileptics.

The compounds of this invention, as depicted in the general formula, can be suitably formulated in physiologically acceptable solutions and carriers to make tablets, syrups, isotonic solutions, injections, suppositories and other dosage forms. Irrespective of the dosage form, the total daily dose of the active compound should be in the range of about 200 to 1000 mg. per day with single dosages ranging from about 50 mg. to about 1000 mg. The dosage can, of course, be adjusted by the attending physician with respect to age, weight and sex of the recipient.

All of the compounds useful in the present invention

are readily available either from chemical manufacturers or can be prepared according to syntheses described in the literature. To facilitate the manufacture of compounds for treating epilepsy, literature references to these syntheses are referred to in the following examples.

The following examples are presented in order to disclose the invention more fully. It should be understood, however, that they are not intended to limit the invention in any way.

10 In each of the hereinafter disclosed Examples I-III and V-X the method for illustrating the efficacy of the specific compounds in rabbits, mice and rats is as follows:

A.—Rabbits

15 The minimum dosage of Metrazole (pentylenetetrazol) which provokes 100% seizures in all the animals is injected in the marginal vein of the ear. This dosage was found to be 30 mg./kg. The preventive product is administered either rectally, intraperitoneally or intravenously from 15 minutes to six hours before the animal is injected with Metrazole. Protection is considered total if no seizure sets in or if the seizure is very considerably reduced in its duration and its intensity in one or the other of the two phases (tonic or clonic). Partial protection is 25 evidenced by the absence of one of the two phases.

B.—Mice

The experiments conducted are classified as follows:

30 (1) The first type is similar to that performed in rabbits except that the dosage of Metrazole must produce death in 95-100% of the animals. This dosage has been found to be 64 mg./kg. given intravenously by the tail vein. This test is described by R. Charonnat et al., Therapie (1958) XIII, 1-16.

35 (2) The second type is a group of tests to determine efficacy against standard maximum electroshock seizures and low frequency electroshock seizures as well as against the usual Metrazole seizure. Since these tests are well recognized in the literature only a brief description will 40 be given.

45 The electrically induced convulsions measure the ability of the drug to prevent the hindleg tonic-extensor component of maximal electroshock seizures (MES test) evoked by supermaximal current employing 50 ma. alternating current, 0.2 second stimulus duration and corneal electrodes. The low frequency electroshock seizures (L.F. EST test) is the ability of the drug to elevate two-fold the threshold of the electroshock seizure induced in mice by electrical current delivered at an intensity twice threshold 50 using 0.2 millisecond pulses, three second stimulus duration at six pulses per second. A Grass stimulator (model S4B) was used for the L.F. test; otherwise, the details of the various procedures, the end points employed in mice, and the characteristics of the electroshock apparatus are 55 described in detail in such references as Swinyard, E. A., Brown, W. C. and Goodman, L. S., in J. Pharmacology and Experimental Therapeutics, vol. 106; 319, 1952. The Metrazole test was carried out by the usual subcutaneous injection of the Metrazole at 85 mg./kg. as described in 60 the preceding literature reference.

C.—Rats

65 These animals were subjected to some of the same standard tests as described in "B(2)" for mice as will be evident later in the disclosure.

3
EXAMPLE I*Di-n-propylacetic acid*

Di-n-propylacetic acid is a colorless liquid and very slightly soluble in water. Its synthesis is described in the literature by E. Oberreit in Berichte, vol. 29, 1998-2001 (1896). Twelve mice were rectally administered 200 mg./kg. of di-n-propylacetic acid in the form of suppositories by mixing the designated dosage in liquefied cocoa butter. After a period of 45 minutes, each mouse was intravenously administered the 64 mg./kg. of Metrazole as described in test No. 1 for mice. Complete protection against death was obtained for 40% of the mice.

Di-n-propylacetic acid was also rectally administered in the described cocoa butter mixture to 12 rabbits in a dosage ranging from 200 mg./kg. to 400 mg./kg. The time interval between administration of the drug and the Metrazole injection is described in Table I along with the results of the test.

TABLE I

Dose of Di-n-propylacetic acid in mg./kg	Number of Animals	Time Interval	Results
200-----	6	1 hr. 45 min-----	2 seizures, 2 partial seizures, 2 total protection.
200-----	2	1 hr-----	2 seizures
300-----	2	1 hr. 45 min-----	Total protection.
400-----	2	1 hr. 45 min-----	Total protection.

4
EXAMPLE II
Sodium-di-n-propylacetate

Sodium di-n-propylacetate is a white powder and is readily soluble in water. The sodium salt is preferably formed from di-n-propylacetic acid by the interaction of sodium hydroxide in an aqueous solution. This procedure is more explicitly set forth in Example XI.

The sodium salt was given intraperitoneally in an aqueous solution to 21 rabbits in dosages ranging from 168 mg./kg.-420 mg./kg. The time after injection when Metrazole was administered varied from 15 minutes to six hours. Substantially complete protection was obtained at a dosage of 200 mg./kg. at a 40 minute period before the injection of Metrazole. Similar experiments were performed using the intravenous route and the same aqueous solution. The threshold of protection and comparable degrees of protection have been found for the following number of rabbits at the described dosages: three rabbits at 25 mg./kg.; three rabbits at 50 mg./kg.; and two rabbits at 100 mg./kg.

Thirty mice were also injected with sodium di-n-propylacetate by the intraperitoneal route, employing a suitable aqueous solution, in the following manner: ten animals received 50 mg./kg.; six were given 100 mg./kg.; 14 were administered 200 mg./kg. They were tested according to procedure No. 1 for mice with a 30 minute time interval between the administration of sodium di-n-propylacetate and Metrazole. The results were as follows: 40% survived with the 50 mg./kg. dosage; 50% survived with 100 mg./kg. and 57% survived at the 200 mg./kg. dosage level.

The efficacy of the sodium salt is further indicated by the protection given to rats when they are subjected to the standard maximal electroshock test. Thirty minutes prior to the shock treatment seven rats were orally administered in aqueous solution 400 mg./kg. of sodium di-n-propylacetate and seven others received orally 800 mg./kg. Those receiving the larger dosage evidenced complete protection in all seven of the animals while three of the seven administered the smaller dose were protected.

Convulsions and seizures were also controlled when sodium di-n-propylacetate was administered to humans

in conjunction with standard anti-epileptic drugs of which phenobarbital, belladonna, diphenylhydantoin or primidone are representative. A typical daily dosage was 50 mg. of phenobarbital, 10 mg. of belladonna and sodium di-n-propylacetate corresponding to 600 mg. of di-n-propylacetic acid.

EXAMPLE III

Comparative anticonvulsant activity

10 The following Tables II and III are presented for the purpose of illustrating certain comparative tests for sodium di-n-propylacetate and four well-known anticonvulsant agents, namely phenobarbital, diphenylhydantoin, trimethadione and phenacemide. In the instance of each compound administered, the recipient mice were male albinos. They were allowed access to water and received the same diet; they were kept under the same conditions prior to administration. Sodium di-n-propylacetate (DPA Sodium) was administered orally, subcutaneously and intraperitoneally in aqueous solutions. Comparative drugs were given orally in aqueous solutions or as suspensions in 6% acacia. The concentration of the drug solution or suspension employed was such that the dose administered per 100 grams body weight was always contained in 1 ml.

15 20 25 30 Table II compares the time for peak effect, as well as the LD₅₀ and TD₅₀ of the sodium salt and the well-known anticonvulsant agents. To determine the time of peak effect, a suitable number of mice were subjected to the standard MES test to determine the ED₅₀ which is a dose which protects 50% of the animals against seizures. Additional mice were then subjected to the MES test at various intervals to determine the time during which the drug manifests its peak effect. In the instance of DPA Sodium, 56 animals were employed in the test and for the remaining drugs, 24 were used for each compound.

35 40 45 The LD₅₀ is the single dose of each compound which was fatal to 50% of the tested animals within 24 hours. In the instance of DPA Sodium, 42 mice were employed in this test, while for the other compounds 24 mice were used for each drug.

50 55 The TD₅₀ is the single dose producing evidence of minimum neurotoxicity in 50% of the mice at the time of peak drug action. The method of its determination will be explained later. The end point of minimum neurotoxicity was motor incoordination, based on the inability of the animal to maintain equilibrium for one minute on a horizontal rod rotating at six revolutions per minute and evidenced by the presence of other overt signs of toxicity such as loss of placing response, decreased skeletal tone, ataxia, etc.

55 It will be noted in both Tables II and III that certain numerical ranges appear beneath an average number. These values represent 95% fiducial limits for the various dosages.

TABLE II

Compound	Time of Peak Effect (Min.)	LD ₅₀ , mg./kg.	TD ₅₀ , mg./kg.
60 DPA Sodium-----	30	1,700 (1,546-1,870)	1,165 (793-1,713)
Phenobarbital-----	180	200 (167-240)	70.0 (58.3-84.0)
Diphenylhydantoin-----	180	490 (295-808)	84.0 (74.3-94.8)
Trimethadione-----	120	1,875 (1,770-1,950)	1,150 (1,055-1,253)
65 Phenacemide-----	45	2,000 (545-799)	660

70 75 From Table II it is evident that DPA Sodium has the fastest peak effect of the drugs tested. It is also one of the least toxic of the group. It has a TD₅₀ about 16.5 times that for phenobarbital and 14 times that for diphenylhydantoin. With respect to the LD₅₀, DPA Sodium, when compared to phenobarbital, has an average LD₅₀ better than eight times greater, and with respect to diphenylhydantoin, better than three times greater.

The comparative anticonvulsant activity is illustrated in Table III for the compounds under consideration. This table compares the protective index of the compounds which is a potency index arrived at by dividing the TD_{50} by the ED_{50} . The ED_{50} as well as the TD_{50} , is calculated on a statistical basis employing a significant number of mice which were given various doses of the drugs and tested at a predetermined time of peak action until at least three points were established in the range between 0 and 100% seizure protection in the instance of the ED_{50} or minimum neurotoxicity with respect to the TD_{50} . The results were then plotted on a logarithmic probability paper and a regression line was fitted to the plotted points. From this plot the respective TD_{50} , ED_{50} and 95% fiducial limits for protection indexes were calculated by the method of Lichfield and Wilcoxon as described in the Journal of Pharmacology and Experimental Therapeutics, 96:99, 1949.

the described cocoa butter mixture one hour before Metrazole injection as described in the preceding paragraph. Ten control mice were also administered the same dosage of Metrazole. In the control group, nine out of ten mice died, while in the group receiving the ethyl ester of di-n-propylacetic acid, five out of ten survived.

EXAMPLE V

Di-n-propylacetamide

10 Di-n-propylacetamide can be prepared according to the method of Fischer and Dilthey, Berichte d. Deutschen Chemischen Gesellschaft, 35, 853 (1902).

15 Thirteen rabbits were rectally administered dosages of the amide compound, in the usual cocoa butter, as outlined in Table IV. The interval between administration of the amide and the Metrazole as well as the results of the test follow in the Table IV.

TABLE III

Compound	MES, mg./kg.	P.I.	L.F. EST, mg./kg.	P.I.	S.C. Met, mg./kg.	P.I.
DPA Sodium.....	605 (484-756)	1.9	330 (226-482)	3.5	265 (151-466)	4.4
Phenobarbital.....	30.0 (23.6-38.1)	2.3	20 (13.3-30.0)	3.5	18.5 (12.7-26.8)	3.8
Diphenylhydantoin.....	14.4 (12.0-17.3)	5.8	25.0 (16.7-37.5)	3.4	Ineffective	
Trimethadione.....	1,190 (1,063-1,333)	1.0	430 (307-602)	2.7	410 (273-615)	2.6
Phenacemide.....	90 (73.2-111)	7.3	82 (58.2-116)	8.1	94 (69.1-129)	7.0

In the foregoing table a total of approximately 95 mice were employed to determine the ED_{50} for sodium di-n-propylacetate. From these and from the TD_{50} values the MES, L.F. EST and S.C. Met tests, the protective indexes were computed. For the other anti-convulsant agents 72 mice were used for each drug for the same purpose.

An evaluation of the protective indexes in Table III indicates the DPA sodium has very favorable indexes. Comparison of the P.I.'s as derived from the various tests indicates that DPA sodium ranks second by the L.F. EST test, second by the S.C. Met test and fourth by the MES test. Thus, DPA sodium has a satisfactory margin of safety. It is also effective in all three standard anticonvulsant tests.

EXAMPLE IV

Ethyl di-n-propylacetate

Ethyl di-n-propylacetate is an oily liquid which has been prepared by Burton, American Chemical Journal, 3, 390 (1881).

The ethyl ester was rectally administered in the herein described cocoa butter mixture to five rabbits in a dosage of 240 mg./kg. One hour thereafter the rabbits were administered the designated dosage of Metrazole. One of the animals was completely protected; two were partially protected; and one was not protected.

The subject compound was also rectally administered in a dosage of 200 mg./kg. in the described cocoa butter mixture to ten mice. They were subjected to the Metrazole test outlined at B(1) for mice, one hour after administration of the ethyl ester. One half of the mice were found to be fully protected from death.

Ten additional mice were rectally given 119 mg./kg. in

TABLE IV

Dose of Di-n-propyl acetamide	Number of Animals	Time Interval (hr.)	Results
70.....	3	1	2 seizures, 1 partial protection.
70.....	2	2	2 seizures.
100.....	6	2	3 seizures, 3 partial protection.
150.....	2	2	1 seizure, 1 partial protection.

55 Ten mice were intraperitoneally administered 180 mg./kg. of the amide compound in an aqueous solution and after a period of one hour were given the Metrazole injection according to Mice Test No. B(1). This resulted in 100% survival of the ten mice. A 50% survival was found when 12 mice were intraperitoneally given 45 mg./kg. in the previously described solution and subjected to the same test.

60 The amide derivative was rectally administered in the described cocoa butter mixture to ten mice in a dosage of 200 mg./kg. Ten additional mice served as a control group. All 20 were subjected after administration to the Metrazole Test No. B(1). All the mice in the control group died while there were no deaths among the mice receiving the amide compound. Among the group receiving the compound, only three had clonic movements of the head with no tonic seizures.

EXAMPLE VI

Di-n-propylacetyl urea

65 Di-n-propylacetyl urea in a colorless crystalline material. Its preparation is described by Fischer and Dilthey in Annalen der Chemie, 335, 367 (1904).

Table V represents the results of previously described rectal administration of various doses of the urea compound administered to 14 rabbits. The number of animals receiving the specified dosages is indicated in Table V along with the time between administration and injection of Metrazole.

TABLE V

Dose of Di-n-propylacetyl urea, mg./kg.	Number of Animals	Time Interval (hr.)	Results
70.	4	1	2 seizures, 2 full protection, 1 partial protection.
70.	2	2	1 seizure, 1 partial protection.
100.	1	1	1 partial protection.
100.	5	2	2 seizures, 2 partial protection, 1 full protection.
150.	2	2	1 partial protection, 1 full protection.

The urea compound was also found effective in 50% of 12 mice when administered rectally in a dosage of 100 mg./kg. according to the procedure outlined in the previous examples and tested according to Test No. B(1) with a one hour interval between administration of the urea derivative and the Metrazole.

Additional tests were conducted on 20 mice. Ten mice rectally received 126 mg./kg. of the urea compound as previously described and ten others served as controls. One hour after administration of the compound, ten mice were given the Metrazole test described in Test No. B(1). In the group not receiving the urea derivative, nine out of ten mice died whereas in the group receiving the urea compound eight out of ten survived.

EXAMPLE VII

Sodium 2-isopropylvalerate

2-isopropylvaleric acid can be prepared by the method of E. Fischer, Holzapfel and Gwinner, Berichte d. Deutschen Chemischen Gesellschaft, vol. 45, p. 256. The sodium salt can be conveniently made according to the procedure described in Example XI.

A dose of the sodium salt equivalent to 200 mg./kg. of the valeric acid was administered intraperitoneally in an aqueous solution to ten mice. The mice were tested against Metrazole according to the procedure outlined for mice at B(1). Ten additional mice served as controls. In the group not receiving the sodium salt, all died while all survived in the group receiving the valeric acid salt.

Eleven rabbits each weighing 2½ kilos were also given intraperitoneally dosages of the sodium salt of the valeric acid compound in an aqueous solution. They were tested according to the procedure outlined under "A-Rabbits." The results are shown in Table VI with the time interval between administration of Metrazole and the valeric acid salt being 40 minutes.

TABLE VI

Dose of Sodium 2-isopropylvalerate, mg./kg.	Number of Rabbits	Results
230.	3	3 partial protection.
345.	4	1 full protection, 3 partial protection.
460.	4	4 partial protection.

EXAMPLE VIII

Sodium di-n-butylacetate

Di-n-butylacetic acid can be prepared by the method of Levene and Cretcher as described in the Journal of Biological Chemistry, vol. 33, p. 508. The sodium salt is prepared according to the procedure described in Example X.

A total of 15 rabbits were administered the sodium salt of di-n-butylacetic acid. The same method for administering and testing the dibutylacetic acid salt in the rabbits was employed as described in the previous example. The results are described in Table VII.

TABLE VII

Dose of Sodium Di-n-butylacetate, mg./kg.	Number of Rabbits	Results
10		
225.	3	2 partial protection, 1 seizure.
337.5.	7	4 total protection, 3 partial protection.
450.	5	4 total protection, 1 partial protection.
15		

It should be noted that with the animals receiving the 337.5 and 450 mg./kg. dosages a hypnotic effect was also observed.

When ten mice were intraperitoneally injected with an aqueous solution of sodium di-n-butylacetate at a dosage of 100 mg./kg. according to the procedure for testing mice as outlined in the previous example, 100% were protected. All the ten mice which served as controls, died.

EXAMPLE IX

1-(di-n-propylacetyl)-5,5-diphenylhydantoin

To a boiling solution of 30.2 g. of 5,5-diphenylhydantoin in 35 ml. of pyridine, 19.5 g. of di-n-propylacetylchloride were added. The resulting mixture was refluxed for ten hours then cooled and diluted with 25 ml. of benzene. The diluted solution was extracted with 70 ml. of a 6 N hydrochloric acid solution. A slight amount of unreacted diphenylhydantoin crystallized and was removed by filtration. The filtrate was transferred into a separatory funnel. The upper organic layer was washed with water and the solvent was removed subsequently by vacuum distillation at 60° C. To the concentrated reaction mixture was added 75 ml. of 90% methanol and 20 ml. of heptane with the desired residue being partitioned between the methanol and the heptane. The methanolic layer was separated, heated to boiling and enough water added to cause a slight turbidity. On cooling the methanolic solution, the product, 1-(di-n-propylacetyl)-5,5-phenylhydantoin crystallized in the form of needles. It was collected on a filter and crystallized from 85% aqueous methanol. The di-n-propylacetyl-5,5-diphenylhydantoin is characterized by its melting point of 150.5-152.5° C.

The acylated hydantoin was administered in a dosage of 200 and 300 mg./kg. by the intraperitoneal route in an olive oil suspension. Eight rabbits were employed and tested according to the herein described procedure for testing rabbits with a 40 minute interval being employed between the administration of the subject compound and the Metrazole.

65 The results as shown in Table VIII.

TABLE VIII

Dose of 1-(di-n-propylacetyl)-5,5-diphenylhydantoin	Number of Rabbits	Results
70		
200.	4	1 total protection, 2 partial protection, 1 seizure.
300.	4	2 total protection, 2 partial protection.

Examples X to XIII illustrate dosage formulations for administering sodium di-n-propylacetate as well as di-n-propylacetic acid, di-n-propylacetamide and di-n-propylacetyl urea. In the instance of Example XI, the formulation of the sodium derivative is described as being made from di-n-propylacetic acid.

EXAMPLE X

Oral solution of 20% sodium di-n-propylacetate

Ingredient:	Amount, grams
Di-n-propylacetic acid	20
Sodium hydroxide 30%	17
Water, q.s.	100

The di-n-propylacetic acid is neutralized with sodium hydroxide and the water is subsequently added to this mixture to form a cloudy solution. The pH is adjusted to 7.5 with the dropwise addition of the sodium hydroxide solution. After adjustment of the pH, the solution subsequently becomes clear. Twenty drops of the formulated solution contain 20 mg. of the acid.

EXAMPLE XI

Di-n-propylacetic acid suppositories

Ingredient:	Amount
Di-n-propylacetic acid	mg 200
Glycocol	mg 200
Cocoa butter, q.s.	g 2

The butter is melted and the di-n-propylacetic acid is admixed therewith. Previously, the glycocol is finely ground, and added to the agitated mixture. The mass is poured into a suitable mold and rapidly cooled.

EXAMPLE XII

Di-n-propylacetamide and di-n-propylacetyl urea suppositories

Ingredient:	Amount
Di-n-propylacetamide	mg 200
Cocoa butter, q.s.	g 2

The butter is melted and the di-n-propylacetamide is dissolved therein. The mixture is cooled slowly while being agitated and is then poured into a suitable mold and cooled rapidly.

The same procedure is employed for formulating 200 mg. suppositories of di-n-propylacetyl urea.

EXAMPLE XIII

Sodium di-n-propylacetate tablets

In illustration of a tablet dosage 1000 tablets each containing 100 mg. of active material were prepared by mixing together 100 grams of sodium di-n-propylacetate, three grams of corn starch and 15 cc. of ethylether. The granulation is forced through a screen and dried. To the dried material is added five grams of talc and two grams of magnesium stearate as lubricants; and twelve grams of additional corn starch as a disintegrator. The material thus prepared is compressed into 1000 tablets each containing 100 mg. of active material. The tablets can be scored if desired so that they can be easily broken in half.

Certain compounds and their formulations have been specifically described in the foregoing examples as anticonvulsant agents. In addition, ethyl-sec.-butylacetic acid as well as ethyl-(1-methyl-butyl)acetic acid and di-hexylacetic acid can also be employed. The first mentioned acid can be prepared by the method of Doran and Shank, JACS, vol. 5, p. 195; the second compound by the method of Cope and McElvain, JACS, vol. 54, p. 4323; and the di-hexylacetic acid according to the method of Armendt

and Adams, JACS, vol. 52, p. 1290. It should be understood that the alkali metal salts of the acids specifically or generally described herein, and whether disclosed in the salt or ester form, can be employed according to the teachings of this invention. Such alkali metal salts include sodium, potassium and lithium. The group of lower alkyl esters formed from the disclosed acids and alcohols containing a total of 1-5 carbon atoms can also be employed; this group includes the methyl, ethyl, propyl and isopropyl esters as well as the esters of the isomeric butyl and pentyl alcohols. In addition, to the salts and the esters previously described, the urea and the amide derivatives of the herein described acids can also be utilized.

Certain literature references have been given with respect to specific compounds. By obvious adaptations of these methods, all of the compounds described herein can be prepared. The esters can be prepared by known procedures from the acids falling within the scope of the general formula and from the corresponding alcohols. The urea and the amides can likewise be prepared, for example, by known methods from the acids by converting them to the acid chloride and further reacting with urea and ammonia, respectively. The chlorides of the acids falling within the scope of this invention can also be utilized to form acid derivatives of 5,5-diphenylhydantoin pursuant to the procedure outlined in Example IX.

It will thus be seen from the foregoing description of the present invention that there are now provided novel anticonvulsant agents which are highly effective yet are low in toxicity. The present anticonvulsant compounds are additionally valuable because they can be administered by several routes without loss of effectiveness. Further, the dialkyl-substituted acetic acids and derivatives thereof provide fast protection and are useful in protection against the various types of seizures in which epilepsy manifests itself.

Others may readily adapt the invention for use under various conditions of service by employing one or more of the novel features disclosed or equivalents thereof. All such which do not depart from the spirit of this disclosure are intended to be within its scope, which at present advised is best defined in the appended claims.

I claim:

1. A method of controlling convulsions and seizures in warm-blooded animals in need of such therapy comprising administering to said animals in an amount sufficient to control convulsions and seizures, a compound of the formula

wherein Alk_1 is lower alkyl containing 2-7 carbon atoms inclusive and Alk_2 is lower alkyl containing 3-7 carbon atoms both forming straight and branched chained alkyl groups; Y is selected from the group consisting of OM, OR, NHZ and 5,5-diphenylhydantoinyl groups, M is selected from the group consisting of hydrogen, sodium, potassium and lithium, R is lower alkyl containing 1-5 carbon atoms inclusive, and Z is selected from the group consisting of hydrogen and carbamyl.

2. A method of controlling convulsions and seizures in warm-blooded animals in need of such therapy comprising administering to said animals an antiepileptic drug and a compound of the formula

wherein Alk_1 is lower alkyl containing 2-7 carbon atoms inclusive and Alk_2 is lower alkyl containing 3-7 carbon atoms inclusive both forming straight and branched

11

chained alkyl groups; Y is selected from the group consisting of OM, OR, NHZ and 5,5-diphenylhydantoinyl groups, M is selected from the group consisting of hydrogen, sodium, potassium and lithium, R is lower alkyl containing 1-5 carbon atoms inclusive, and Z is selected from the group consisting of hydrogen and carbamyl.

3. A method of controlling convulsions and seizures in warm-blooded animals in need of such therapy comprising administering to said animals an anti-epileptic drug and a compound of the formula

wherein Alk₁ is lower alkyl containing 2-7 carbon atoms inclusive and Alk₂ is lower alkyl containing 3-7 carbon atoms inclusive both forming straight and branched chained alkyl groups and Y is selected from the group consisting of amino and ureido.

4. A method of controlling convulsions and seizures in warm-blooded animals in need of such therapy comprising administering to said animals in an amount sufficient to control said convulsions and seizures, a compound of the formula

wherein R is lower alkyl containing 1-5 carbon atoms inclusive.

5. A method of controlling convulsions and seizures in warm-blooded animals in need of such therapy which comprises administering di-n-propylacetate to said animals in an amount sufficient to control said convulsions and seizures.

6. A method of controlling convulsions and seizures in warm-blooded animals in need of such therapy which comprises administering sodium di-n-propylacetate to said animals in an amount sufficient to control said convulsions and seizures.

7. A method of controlling convulsions and seizures in warm-blooded animals in need of such therapy which comprises administering ethyl di-n-propylacetate to said animals in an amount sufficient to control said convulsions and seizures.

8. A method of controlling convulsions and seizures in warm-blooded animals in need of such therapy which comprises administering di-n-propylacetamide to said animals in an amount sufficient to control said convulsions and seizures.

9. A method of controlling convulsions and seizures in warm-blooded animals in need of such therapy which comprises administering di-n-propylacetamide urea to said animals in an amount sufficient to control said convulsions and seizures.

10. A method of controlling convulsions and seizures in warm-blooded animals in need of such therapy which comprises administering sodium 2-isopropylvalerate to said animals in an amount sufficient to control said convulsions and seizures.

11. A method of controlling convulsions and seizures in warm-blooded animals in need of such therapy which comprises administering sodium di-n-butylacetate to said animals in an amount sufficient to control said convulsions and seizures.

12. A method of controlling convulsions and seizures in warm-blooded animals in need of such therapy which comprises administering 1-(di-n-propylacetyl)-5,5-diphenylhydantoin to said animals in an amount sufficient to control said convulsions and seizures.

12

13. A method of controlling convulsions and seizures in warm-blooded animals in need of such therapy comprising administering to said animals an anti-epileptic drug and sodium di-n-propylacetate.

14. A therapeutic composition useful in the control of convulsions and seizures in warm-blooded animals in need of such therapy comprising an effective amount of a compound of the formula

wherein Alk₁ is lower alkyl containing 2-7 carbon atoms inclusive and Alk₂ is lower alkyl containing 3-7 carbon atoms inclusive both forming straight and branched chained alkyl groups; Y is selected from the group consisting of OM, OR, ureido and 5,5-di-phenylhydantoinyl groups; M is selected from the group consisting of hydro-

gen, sodium, potassium and lithium, R is lower alkyl containing 1-5 carbon atoms inclusive and a physiologically acceptable solid or fluid carrier for said compound where in the instance said fluid is water the resulting composition is sterile.

15. A therapeutic composition useful in the control of convulsions and seizures comprising an effective amount of a compound of the formula

wherein R represents straight or branched chained lower alkyl containing 1-5 carbon atoms inclusive and a physiologically acceptable solid or fluid carrier where in the instance said fluid carrier is water, the resulting composition is sterile.

16. A therapeutic composition useful in the control of convulsions and seizures comprising an effective amount of di-n-propylacetate and a physiologically acceptable solid or fluid carrier where in the instance said fluid is water the resulting composition is sterile.

17. A therapeutic composition useful in the control of convulsions and seizures comprising an effective amount of sodium di-n-propylacetate and a physiologically acceptable solid or fluid carrier where in the instance said fluid is water the resulting composition is sterile.

18. A therapeutic composition useful in the control of convulsions and seizures comprising ethyl di-n-propylacetate present in the range of about 50 mg. to about 1000 mg., and a solid physiologically acceptable carrier in a unit dosage form.

19. A therapeutic composition useful in the control of convulsions and seizures comprising di-n-propylacetyl urea present in the range of about 50 mg. to about 1000 mg., and a solid physiologically acceptable carrier in a unit dosage form.

20. A therapeutic composition useful in the control of convulsions and seizures comprising sodium 2-isopropylvalerate present in a range of about 50 mg. to about 1000 mg., and a solid physiologically acceptable carrier in a unit dosage form.

21. A therapeutic composition useful in the control of convulsions and seizures comprising 1-(di-n-propylacetyl)-5,5-diphenylhydantoin present in the range of about 50 mg. to about 100 mg., and a solid physiologically acceptable carrier in a unit dosage form.

22. A therapeutic composition useful in the control of convulsions and seizures comprising sodium di-n-butylacetate present in a range of about 50 mg. to about 100 mg., and a solid physiologically acceptable carrier in a unit dosage form.

23. 1-(di-n-propylacetyl)-5,5-diphenylhydantoin.
